UNITED STATES PATENT OFFICE.

CHARLES POHL, OF LOS ANGELES, CALIFORNIA.

GUN SIGHT.

1,421,553.

Specification of Letters Patent.

Patented July 4, 1922.

Application filed April 21, 1920. Serial No. 375,451.

To all whom it may concern:

Be it known that I, CHARLES POHL, a citizen of the United States, residing at Los Angeles, in the county of Los Angeles and 5 State of California, have invented new and useful Improvements in Gun Sights, of which the following is a specification.

This invention relates to a gun sight which is especially applicable for use on the types 10 of guns employed by hunters, such as shot guns and the like.

It is the object of this invention to provide a gun sight which is particularly adapted for sighting a moving object, whereby the 15 object may be covered while in motion and the shot fired such distance in advance of the object as to compensate for distance traversed thereby after discharge of the gun, thereby reducing the possibility of a miss.

20 Another object is to provide a gun sight of the above character which is so formed that on covering the object through the sight the gun may be pointed at points various distances in advance of the object according to 25 the judgment of the marksman.

A further object is to provide a gun sight of the class specified which may be readily applied to the ordinary double barrel shot guns and adjusted to various positions there- 30 on according to the range desired.

Other objects will appear hereinafter.

The invention is illustrated in the accompanying drawings, in which:—

Figure 1 is a perspective view of a gun 35 showing the gun sight as applied.

Figure 2 is a diagram illustrating the principle of the operation of the invention.

Figure 3 is a view of the gun sight as seen in front elevation.

40 Figure 4 is a view in horizontal section as seen on the line 4—4 of Figure 3.

More specifically 5 and 6 indicate the barrels of a shot gun, and 7 designates the sight ridge extending lengthwise of the barrels on 45 the upper side thereof, and which sight ridge is formed with side walls slightly tapered inwardly from their upper edges.

In carrying out my invention I provide a 50 bar 8 adapted to be mounted on the gun barrels to extend transversally thereof, and for which purpose the under side of the bar is formed with a pair of concave faces 9 and 10 adapted to seat on and conform to the upper curved surfaces of the gun barrels, as shown 55 in Figure 3, and is also formed with a recess 11 to receive the ridge 7 and which recess is

formed with inclined side walls 12 adapted to conform to the side walls of the ridge 7. The ridge is tapered lengthwise of the gun barrels so that its outer portion is narrower 60 than the inner portion thereof, which permits the bar being positioned with the recess 11 disposed astride the ridge at a point where the latter is sufficiently narrow to enter the recess so that on sliding the bar toward the 65 gun stock the side walls of the ridge will be brought into frictional engagement with the side walls 12 forming a dove tail connection between the bar and gun, thus rigidly holding the bar in place.

70 Formed in the bar intermediate its ends is a sight opening 14 which opens at its lower portion to the upper face of the sight ridge 7, so that sight may be taken along the ridge in the ordinary manner, and formed through 75 the bar on each side of the central opening 14 is a series of sight openings 15 of any suitable number and which openings are disposed on the same plane and are formed on a radius struck from a point on a center line 80 passing through the center of the intermediate sight opening 14 and constituting the center line of the sight ridge, the radial point corresponding to the ordinary position of the eye in sighting along the sight ridge. The 85 oblique sight openings on one side of the center of the bar thus extend in directions at angles to those on the other side, as indicated on an exaggerated scale in Figure 4.

These sight openings 15 are designed to be 90 employed in sighting an object moving in substantially a horizontal direction as will be later described. For the purpose of sighting an object moving in substantially a vertical direction the bar is formed with a central upwardly extending point or tip 16 and a sight opening 17 positioned intermediate the tip and the central opening 14.

95 In the operation of the invention the sight is applied to the gun barrels as before described and is disposed thereon according to the position of the eye in relation to the radial sight openings 15 so that the line of sight would pass centrally through any one of the openings. The normal or proper position of the sight on the gun may be determined by forming the latter with indicia or gauge marks 19, as shown in Figure 1, which marks may be graduated to enable disposing of the sight at various positions according to 100 the range.

105 In firing at a moving object the marks-

man judges approximately the distance of the object and its speed, for example, assume the object to be a bird flying to the right at a distance of 350 feet and at such speed that 5 the marksman would ordinarily sight the gun along the sight ridge at a point about 8 feet in advance of the bird. In using my gunsight, the marksman would cover the bird through the end sight opening 15 on the 10 left hand end of the bar. On covering the bird through this opening the gun would be pointed towards a point about eight feet in front of the bird, so that on firing the charge, the shot and the bird would reach such point 15 at substantially the same time, thus insuring against a miss. In like manner the marksman on judging the distance and speed of the bird would employ any one of the sight openings accordingly, as indicated diagrammatically in Figure 2.

In the event the bird dropped substantially vertical the marksman would take sight either over the tip 16 or through the sight opening 17 according to the distance of 25 the bird.

In taking aim with the gun sight the bead 20 at the gun tip is not employed except on firing point blank, at which time it would be used in the ordinary manner and sight taken 30 along the ridge 7 through the opening 14. By shifting the gun sight towards or away from the normal position of the eye the divergence through the sight openings may be increased or diminished to meet varying conditions, for example in moving the gun sight 35 closer to the eye as indicated by the dotted

lines *a* in Figure 2 the line of sight will diverge at a greater angle relative to the gun barrel, and by moving it further away the lines of sight would extend at lesser angles. 40

From the foregoing, it will be seen that I have provided a simple gun sight for facilitating firing at a moving object which can be readily applied and easily operated.

While I have shown and described a specific embodiment of my invention, I do not limit myself to the exact details of the construction shown, but may resort to any modifications or changes thereof, as occasion may require and as may come within the scope of 45 the appended claims. 50

I claim:

1. A gun sight comprising a bar adapted to be positioned transversely of a gun barrel and formed with a series of sight openings 55 arranged in a row extending on the opposite sides of the center and radially from a point on a line passing through the center of the bar at right angles thereto.

2. In a gun sight, the combination with a 60 gun having a sight ridge, a bar, and means formed on said bar for engaging said sight ridge to dispose the bar transversely of the gun, said bar being formed with a row of sight openings with a central opening open 65 at its under side to the upper face of the sight ridge, and with the openings on the opposite sides of the center opening diverging progressively on radii struck from a remote point on a line extending centrally of 70 the sight ridge.

CHARLES POHL.
